DROPPING BOTTLE

Eugen Böhm, Ernstthal-on-the-Rennsteig, Germany, assignor to Glashütte Brehmenstall, Septimus Bohn Jr., Ernstthal-on-the-Rennsteig, Germany

Application July 27, 1935, Serial No. 33,439½
In Germany August 7, 1934

7 Claims. (CL 221—148)

This invention relates to dropping bottles and more particularly to dropping bottles of the type in which the capillary tube projecting from the neck of the bottle as well as the air feeding opening are covered and closed by a cap.

Heretofore the capillary tube, hereafter called the tube, of such dropping bottles was fitted in the bore-hole of a cork closing the neck of the bottle. The bore-hole as well as the tube were 10 upwardly tapered and therefore a slight pressure from above easily caused the tube to drop into the bottle; as the cap was clamped strongly upon the cork, it often happened that in removing the cap the cork with the tube was also 15 removed out of the bottle.

My present invention has for its object to improve said type of dropping bottles having a capillary tube and a closing cap. According to one form of my invention the tube is mounted directly on a cross wall of the neck of the bottle, 20 said neck being constructed as a screw threaded projection carrying the cap. In this embodiment of the invention the tube and the bottle consist of one piece and are closed simultaneously by the screw cap together with the air feeding opening.

A further feature of my invention is the arrangement of a longitudinal slot in said tube and the arrangement of the air feeding opening immediately next to the mouth of the tube in the 30 screw threaded projection. This construction offers the advantage that the bottle can be pressed or moulded in a very simple and inexpensive pressing mould.

The threaded projection and the tube are preferably inclined in respect to the longitudinal axis of the bottle. This causes the user to hold the bottle in its correct position with downwardly directed tube.

The longitudinal slot of the tube extends preferably on the lower side of the tube and the air feeding opening is arranged below said tube when the bottle is in position for use. This construction has the great advantage that when the bottle 45 is raised after its use, the final remaining drop is sucked up by the slot of the tube and reconducted into the bottle.

According to another embodiment of my invention the screw thread for the reception of the 50 screw cap is on the lower end of the tube immediately in front of the cross wall of the neck of the bottle. In this case the screw cap has on its opening a packing surrounding the tube and resting against the cross wall of the neck of the 55 bottle, this packing also tightly sealing the air

opening at the same time. This construction offers the advantage that the space between cap and tube becomes very narrow so that only very little amounts of liquid can accumulate while the cap is screwed upon the bottle. A further advantage of this construction is that no threaded socket projection need to be provided which sometimes hinders the entering of the air into the bottle so that the dropping becomes irregular.

In order to use my dropping device also for ordinary screw threaded bottles, the cross wall of the neck of the bottle carrying the tube with the screw cap can be arranged on an intermediate cap-like piece screwable upon such a bottle.

Another form embodying my invention consists in arranging the tube and the air feeding opening in a funnel or groove. This construction offers the advantage that the device is well tightened while locked as the inner and upper part of the screw cap rests firmly upon the upper edge of 20 the funnel. This construction further insures that after use of the bottle a drop can not run along the outer wall of the bottle as it is caught by the funnel.

The construction may be effected in such a 25 way that the tube and the air feeding opening are moulded into the body of the funnel which means an especially simple and inexpensive manufacture and a very unbreakable arrangement of 30 this kind of device.

It is a further object of my invention to change 35 ordinary bottles not having a dropping device into dropping bottles in so constructing the device of my invention consisting of the funnel into which the tube and the air feeding opening are moulded that it can be screwed upon the screw threaded socket of an ordinary bottle. For this purpose the funnel can be provided with a flange which is pressed by a threaded intermediate piece upon 40 a packing provided between the funnel and the threaded socket of the neck of the bottle.

For illustrating the invention several forms of 45 its embodiment are shown in the accompanying drawings.

Fig. 1 shows a dropping bottle according to the invention partly in longitudinal cross-section.

Fig. 2 is a cross-section on lines A—B of Fig. 1.

Fig. 3 shows a modified form partly in longitudinal cross-section.

Fig. 4 shows a modified form partly in longitudinal cross-section.

Fig. 5 shows a modified form partly in longitudinal cross-section.

Fig. 6 is a plan end view on the device of Fig. 5.

Fig. 7 shows a modified form partly in longitudinal cross-section.

Figs. 8 and 9 show a modified form partly in longitudinal cross-section.

- 5 In Figs. 1 and 2 a threaded projection *b* is arranged somewhat inclined to the longitudinal axis of the body *a* of the bottle. A capillary tube *c* extends from this projection parallel to its axis which tube on account of its capillarity sucks up 10 the liquid out of the bottle. Through the opening *d* arranged in the projection *b* next to the end of the tube *c* air may enter into the bottle for replacing the liquid. The bottle is closed by screwing on the screw cap *e* shown in dotted lines in 15 Fig. 1 and which may be made of pressed material or the like. This cap *e* rests on a flange *g* provided on the threaded projection the tightening being secured by the intermediate packing *f*. In the horizontal position illustrated in Fig. 1 and 20 the cap being removed, the fluid drops out of the bottle. The diameter of the tube *c* and the size of the air feeding opening *d* are to correspond to the special requirements, for instance to the viscosity of the liquid.
- 25 The tube *c* is slotted and the air feeding opening *d* connects directly to the tube. This modification has the advantage that the whole bottle including the tube can be pressed or moulded from one piece.
- 30 The oblique arrangement of the threaded socket and of the tube facilitates the proper use of the bottle as the bottle can drop only if the tube is downwardly directed.

In the form of construction shown in Fig. 3 a 35 illustrates the body of the bottle, *b* a projection inclined to the longitudinal axis of the bottle bearing the tube *c* which is longitudinally slotted. Next to the tube is the air opening *d* through which the air enters during the dropping of the 40 liquid. The tube is provided immediately in front of the cross wall of the neck with the screw thread *m* on which a cap *n* closely surrounding the tube can be screwed. The cap *n* is provided on its mouth with a packing *o* which rests against the 45 cross wall of the projection *b* of the neck of the bottle and which is broad enough to also cover and to close up tightly the air opening *d* so that no air can enter the interior of the bottle and no liquid can come into the hollow space between the cap 50 *n* and the tube *c* while the bottle is locked. The route of the air entering during the dropping to the surface of the liquid has become shorter by the length of the screw threaded socket of the construction shown in Figs. 1 and 2 which is not 55 present in this construction. By this the friction of the air is correspondingly diminished and a more uniform dropping attained.

In the form of construction of Fig. 4 the tube *c* with its screw cap *n* and the air opening *d* is 60 arranged on a threaded connecting piece *q* which can be screwed upon a screw *p*¹ of the neck of a bottle *p*. This connecting piece *q* carries with its cross wall the dropping device and can consist of glass or pressed material or the like. The 65 dropping device of this construction can be used with and in connection with every ordinary bottle provided with a suitable thread.

In the form of construction of Fig. 5 the body *a* of the bottle carries a screw threaded projection *b* having a funnel like prolongation *g* which is covered by a screw cap *e* shown in dotted lines. The packing *f* of the cap *e* rests in the locked position of the cap upon the upper border of the funnel like prolongation thus closely tightening the 70 bottle.

The funnel *g*, as shown in Fig. 6, is filled for about one third with glass the tube *c* being pressed or moulded into this mass of glass. The air feeding opening *d* is arranged in the bottom of the funnel, respectively in the front face of the screw threaded projection *b*. The upper border of the funnel *g* projects somewhat over the end of the tube *c*. This construction makes it impossible that at the end of the use of the bottle the last drop can run along the outer wall of the bottle. 10

In the form of construction of Fig. 7 the funnel *g* with the tube *c* and the air opening *d* is mounted on the projection *b* of the bottle by means of an intermediate cap like piece *g*² having a flange engaging with a flange *g*³ of the funnel and a thread for being screwed on the threaded projection *b*. An annular packing *g*⁴ is provided between socket *b* and flange *g*³. The funnel with the dropping device can be screwed upon any bottle having a corresponding threaded projection; it may be made from glass, pressed or moulded material or the like. 20

In the form of construction shown in Figs. 8 and 9 a projecting part *c* containing the tube *c*¹ is arranged on the neck *b* of the bottle *a*. The tube *c*¹ as shown in the figures is slotted on its lower side. The air feeding opening *d* is provided in the projecting part *c* below the tube. If the bottle is used it is held with part *c* pointing downwards this position resulting automatically from the oblique direction of the part *c*. This guarantees the correct position of the slot of the tube and of the air feeding opening. If this type of bottle is so constructed that part *c* lies in the longitudinal axis of the bottle, it will be necessary 30 to provide a marking for the proper position. 35

If the bottle is lifted after use the final last drop *e* (Fig. 9) will be sucked up by the slotted tube and reconducted into the bottle. Normally the arrangement of the slot on the lower side of the tube and of the air feeding opening below said tube do not offer any inconvenience as the sucking power of the capillary tube does not allow any liquid to escape from the air opening or from the longitudinal slot of the tube. 40 45

It will be understood that various changes in the details of construction may be made without departing from the spirit or scope of the invention as defined by the appended claims. 50

I claim:

1. A drop bottle of the type described including in combination, a body portion, a neck provided with a transverse wall integral therewith and a capillary channel extending integrally from said wall, said wall being provided with an air inlet. 55

2. A drop bottle of the type described including in combination, a body portion, a neck, a transverse wall integral with and closing said neck, a rod extending integrally from said wall 60 and having a capillary groove extending longitudinally for the full length thereof, said wall being provided with an air inlet and a liquid outlet to said groove.

3. A drop bottle of the type described including in combination, a body portion, a neck, a transverse wall integral with and closing said neck, a rod extending integrally from said wall and having a deep capillary groove pressed into the full length thereof, said wall being provided with an air inlet therethrough merging with the lower end of said groove. 70

4. A drop bottle of the type described including in combination, a body portion, a neck, a 75

transverse wall integral with and closing said neck, a capillary channel extending integrally from said wall, said wall being provided with an air inlet, a cap to cover the channel and close the air inlet and a screw thread on said channel to receive the cap.

5. A drop bottle of the type described including in combination, a body portion, a neck, a transverse wall integral with and closing said neck, a capillary tube extending integrally from said wall and neck, said transverse wall and tube being inclined with respect to the axis of the bottle body.

10 6. A drop bottle of the type described including in combination a body portion, a neck, a transverse wall integral with and closing said

neck, a rod integral with and extending from said wall at an angle to the axis of the bottle body and having a deep capillary groove pressed into the full length thereof on the side nearest to the bottom of the bottle, and an air inlet through 5 said wall and in communication with said groove whereby it and the groove are beneath the tube when the bottle is in use.

7. A drop bottle according to claim 3 in which the grooved rod and air inlet are inclosed in a 10 cylindrical sleeve formed integral with the transverse wall and groove rod, the whole being formed by molding during the forming of the bottle.
